(57) CLAIM

The ornamental design for a pedicure spa, as shown and described.

DESCRIPTION

FIG. 1 is a perspective view showing the front, right, and upper side of a pedicure spa showing my new design;

FIG. 2 is a right side view thereof;

FIG. 3 is a front view thereof;

FIG. 4 is a top view thereof; and,

FIG. 5 is a rear view thereof.

The broken lines are for illustrative purposes only and form no part of the claimed design.
